UNITED STATES PATENT OFFICE.

LEWIS L. SCOTT, OF ST. LOUIS, MISSOURI, ASSIGNOR TO ELECTROL, INC. OF MISSOURI, OF ST. LOUIS, MISSOURI, A CORPORATION OF MISSOURI.

COMBUSTION SYSTEM.

Application filed May 21, 1921. Serial No. 471,414.

This invention relates to a combustion system used in connection with a steam boiler and is particularly suited for use in steam automobiles. The invention, however, is not limited, in application, to generating steam, and is equally adaptable to use in hot water heaters, and generally, to domestic or commercial oil burners for heating purposes. The general object of the invention is to provide a simple and reliable igniting device for a fuel of the atomized type. This general object is attained by the provision of an auxiliary gas-burning igniting device, of means for igniting the gas thereof and of means for controlling the period of operation of said device.

Other objects, characteristics and advantages of the invention will be pointed out hereinafter.

20 In the accompanying drawings—

Figure 1 is a vertical sectional view through the steam generator and parts associated therewith, all of which are more or less diagrammatic; and

25 Figure 2 is a sectional view of a gas mixing nozzle employed.

Referring to the drawings, the numeral 1 indicates the coils of a semi-flash steam generator, in which water enters at the point 30 2, and steam is delivered from the top coil 3. The boiler coils are surrounded by the shell 4, which shell forms a combustion chamber 5 just above the top coil 3. An air duct 6 is formed by the upper part of the shell 4 to which is attached an air blower 7 in which is mounted the blower wheel 8. An electric motor 9 is mounted on the blower case 7, said motor driving the blower wheel 8, a water pump 10 and a fuel pump 11.

40 Water is supplied to pump 10 from a tank 12 through the pipe 13 and is delivered to the boiler coil 2 through a pipe 14 having a check valve 15.

Combustion fuel, such as kerosene, is supplied to the pump 11 from a tank 16 through a pipe 17 and is delivered to a spray nozzle 18 through a pipe 19. The spray nozzle 18 may be of any well known form and is for the purpose of dividing the fuel into a very fine spray. A pipe 20 leads from pump 11 to the Bourdon tube 21 of a kerosene pressure gage 22. The back of the kerosene pressure gage is shown in the drawing. On the end of the Bourdon tube 21 is secured a pin 23 which projects through a slot 24 in

the back of the gage. An arm 25 is pivotally mounted at the point 26 on the back of the gage 22, and normally bears on an electric contact screw 27, which is insulated from the gage. The arm 25 is grounded in 60 an electric circuit to be referred to. The numeral 28 indicates a steam gage, the back only of which is shown. A pipe 29 connects the Bourdon tube 30 of the steam gage with the steam pipe 3. On the end of the 65 Bourdon tube 30 is secured a pin 31 which projects through a slot 32 in the back of the gage. An arm 33 is pivotally mounted at the point 34 on the back of the gage 28, and normally bears on the electric contact 70 screw 35, which is insulated from the gage. The arm 33 is grounded in the electric circuit to be referred to.

A battery 36 supplies electric current to operate the motor 9. One side of the battery 75 is grounded and the other side connects to a magnet switch 37 through the hand switch 38 and wire 39. The numeral 37^a indicates the armature of the magnet switch, and a wire 40 runs from said armature to the motor 9. One terminal of the motor 9 is grounded. A wire 41 connects to wire 40 and leads to the vibrating spark coil 42 and to the coil 46 of a magnet valve 43. A return wire 44 leads from said coil to one terminal 80 of the secondary winding of the spark coil and thence to the insulated screw 27 on the kerosene pressure gage 22. The other terminal of the secondary winding is grounded. The numeral 45 indicates a tank which is 85 adapted to contain acetylene gas. A pipe 45^a leads from said tank into a valve chamber 45^b of the magnet valve, the mouth of said pipe being normally closed by a valve 48 on an armature 47, normally pressed upward by 90 a spring 53. When an electric current is sent through the coil 46 of the magnet valve 43, the armature 47 moves downward and opens the valve 48 and allows acetylene gas to pass from the tank 45 to the mixing nozzle 100 49 through a pipe 49^a. The valve 48 is normally held closed by the spring 53. Said gas is mixed with air in the mixing nozzle, which is supplied through the small holes 50 (see Fig. 2), and the mixture is conducted by a 105 pipe 49^b to a small ignition chamber 51 where it is ignited by a spark plug 51^a. The spark plug is connected to the primary of the spark coil 42 through the wire 52. A pipe 54 conducts the ignited gas into a 110

chamber 55 provided above the combustion chamber 5, and the ignited gas enters chamber 55 just below the point where the combustion fuel is sprayed from the nozzle 18.

5 The operation is as follows:

Upon closing the switch 38 the motor 9 will be started and thus place in operation the water pump 10, the fuel pump 11 and the blower wheel 8. Water will thereupon 10 be forced into circulation through the boiler tubes 1 and fuel will be forced through the spray nozzle 18, whence it issues in the form of a fine spray into the chamber 55 where the fuel spray is mixed with air from the blower 15 8. The closing of the switch 38 will also operate to place the spark plug 51 and the magnet valve 43 into the circuit of the battery 36. The armature 47 will thereupon be drawn downward, removing valve 48 20 from the mouth of pipe 45^a, thereby admitting acetylene gas to valve chamber 45^b. From this valve chamber the gas passes through pipe 49^a into the mixing nozzle 49 where it is mixed with air, and the mixture 25 then passes through pipe 49^b to the ignition chamber 51, where it is ignited by the spark plug 51^a. The flame of the ignited acetylene gas is projected into the chamber 55 and ignites the fuel sprayed from nozzle 18.

30 Igniting a sprayed fuel directly by means of a spark plug is well known. It is also well known to ignite fuel by means of a gasoline pilot light, which light requires considerable time to get started and when 35 once started is kept burning. The pilot light is unreliable, because it will clog with carbon and go out at a time when most needed.

While it is possible to ignite sprayed kerosene fuel directly with an electric spark, this 40 method is not absolutely reliable. It is necessary to place the spark plug in a zone where the fuel mixture is very rich and the plug will collect carbon in a comparatively 45 short time and fail to light the fuel spray, with the result that the combustion chamber will be filled with unburned fuel.

A highly important feature of my invention is that I ignite with an electric spark

a gas that can easily be ignited and that will 50 not foul the spark plug, and by means of the hot flame of this ignited gas ignite the fuel spray. Another important feature of my invention is that the spark plug and acetylene flame only operate for a short time, say, 55 two seconds, in lighting the fuel spray and are automatically shut off after this short period of operation.

The shutting off of the acetylene gas and the electric spark is brought about in the 60 following manner:

The normal fuel pressure used is about fifty pounds. When the kerosene gage 22 indicates forty pounds pressure, the pin 23 will contact with the arm 25 and will break the electric circuit to the spark plug 51 and magnet valve 43. This switch will remain open as long as the motor 9 is running and the fuel pressure is fifty pounds. Shortly after the motor 9 is put into operation, 70 steam will be generated in the boiler coils 1. When the steam has reached 600 pounds pressure, the pin 31 on the Bourdon tube 30 will contact with the arm 33 and break the electric circuit to the motor, spark coil and magnet valve 43, through the magnet switch 37. It will be understood, of course, that when the circuit to the magnet switch is broken, the armature 37^a drops, thus breaking the main circuit over wire 40. 80

What I claim as new is:

In combustion apparatus for burning heavy oils, in combination with a heat absorbing medium, a fuel burning device associated therewith, means for supplying an 85 oil fuel thereto, an auxiliary ignition device for said fuel comprising means for supplying an independent gas fuel, a magnet valve for controlling the supply of said gas fuel, electrically operated means for igniting the gas fuel, a circuit including said igniting means and the magnet of said valve, and automatic means governed by conditions of operation of the apparatus for controlling said circuit. 90 95

In testimony whereof, I have hereunto set my hand.

LEWIS L. SCOTT.
